CHILD'S SAVINGS BANK

James Donald Johnson, 5015 Bear Ave. NE,
Cannonsburg, Mich.

Filed May 25, 1962, Ser. No. 70,286

Term of patent 14 years

(Cl. D34—11)

FIG. 1

The side, bottom, and rear of the article not shown are plain.

I claim:

The ornamental design for a child's savings bank, as shown and described.
